Max Sternberg, San Francisco, Calif.

Application March 13, 1944, Serial No. 112,890

Term of patent 14 years

(Cl. D48—27)

To all whom it may concern:

Be it known that I, Max Sternberg, a citizen of the United States, residing in the city and county of San Francisco, State of California, have invented a new, original, and ornamental Design for Cigarette Lighters, of which the following is a specification, reference being had to the accompanying drawing, forming part thereof.

I claim:

The ornamental design for a cigarette lighter, as shown.

M. STERNBERG.
